[57] CLAIM

The ornamental design for a wall clock or the like, as shown and described.

DESCRIPTION

FIG. 1 is a front and top-right perspective view of a wall clock showing my new designs;

FIG. 2 is a front elevational view thereof;

FIG. 3 is a right side elevational view thereof;

FIG. 4 is a bottom plan view thereof;

FIG. 5 is a top plan view thereof;

FIG. 6 is a left side elevational view thereof; and,

FIG. 7 is a rear elevational view thereof.

The broken away cord shown in FIGS. 2 and 7 have been omitted from FIGS. 1 and 3-6 for ease of illustration.
